DESIGN FOR A BOTTLE

Stewart S. Freedman, Cincinnati, Ohio, assignor to Kelmar, Inc., Cincinnati, Ohio, a corporation of Ohio

Application September 17, 1936, Serial No. 64,903

Term of patent 3½ years

To all whom it may concern:

Be it known that I, Stewart S. Freedman, a citizen of the United States, residing at Cincinnati, Hamilton County, Ohio, have invented a new, original, and ornamental Design for a Bottle, of which the following is a specification, reference being had to the accompanying drawing, forming a part thereof, and in which:

Fig. 1 is a top plan view of a bottle showing my new design;

Fig. 2 a face view; and

Fig. 3 an edge view thereof.

I claim:

The ornamental design for a bottle as shown.

STEWART S. FREEDMAN.
